UNITED STATES PATENT OFFICE.

LOUIS SANDERS, OF BROOKLYN, NEW YORK.

DESIGN FOR A BELT.

SPECIFICATION forming part of Design No. 27,689, dated September 28, 1897.

Application filed June 21, 1897. Serial No. 641,720. Term of patent 7 years.

To all whom it may concern:

Be it known that I, LOUIS SANDERS, a citizen of the United States, residing in Brooklyn, in the county of Kings and State of New York, have invented and produced a new and original Design for Belts, of which the following is a specification, reference being had to the accompanying drawing, forming a part thereof, which represents a perspective view of a belt embodying the features of my design.

The feature of the design consists of a horizontal chain A of loops B, which appear upon the inner face of the belt C. The open portions of alternate loops face in opposite direc-

tions, the open portion of one loop facing upwardly and the open portion of the next loop facing in a downwardly direction. The bodies of the loops are approximately circular, and the open mouth portion of one loop forms a portion of the body of a loop upon either side. The horizontal chain of loops appears as attached at its ends to the belt.

I claim—

The design for a belt herein shown and described. 25

LOUIS SANDERS.
